UNITED STATES PATENT OFFICE

BLUFORD W. BROCKETT, OF CLEVELAND HEIGHTS, OHIO, ASSIGNOR, BY DIRECT AND MESNE ASSIGNMENTS, OF ONE-HALF TO THE AMERICAN LAUNDRY MACHINERY COMPANY, OF CINCINNATI, OHIO, A CORPORATION OF OHIO, AND ONE-HALF TO UNITED STATES HOFFMAN MACHINERY CORPORATION, A CORPORATION OF DELAWARE

POWER PRESS

Application filed September 6, 1923. Serial No. 661,207.

This invention relates to presses of the laundry and garment press type utilized for pressing materials including under and outer garments.

Laundry and garment presses have been constructed in various ways and a very popular type, and the one to which this invention is particularly directed, comprises a frame supporting a buck or bed adapted to be engaged by a coextensive head for pressing the garment upon the buck or bed. These presses have been provided with various types of mechanism for moving the head into engagement with the bed and some of these arrangements have been foot or hand operated and others power operated. Still others contain both types of mechanism. In the power operated machines the head is closed and brought to pressure position upon the bed in part cycles, so to speak; that is, the garment is arranged upon the bed and a controller is operated to cause the power means to bring the head down upon the article and hold it under pressure until it is released. In the operator-operated machine the head is brought down by foot or by hand and locked in engagement with the garment. In the third type, comprising the operator-closed power pressure arrangement, the head is closed by hand or foot upon the work and thereafter power is applied to the parts for final pressure of the garment.

The present invention is applicable to the power-closed and opened machine and is somewhat like that type but differs therefrom by the fact that while the old type of machine operates in fixed cycles depending upon the operation of the controller, yet the closing and opening operations or cycles of my present machine may be interrupted at any stage, by the operator as may be desired. For example, the operator may start the head at full speed towards closed position, may slow down the closing movement just as the head reaches the garment, he may stop the movement of the head before it reaches the garment and let it remain in such position, or he may release it to full open position. It is possible with the present arrangement to close the machine with a squeeze without ex-

treme pressure and then open the machine, or it is possible to carry the closing operation through to final heavy pressure, to hold this pressure and then release the machine to fully open position. It is also possible by a rapid manipulation of the control, as will appear, to produce a repeated, rapid closing and opening of short range for the production of a "padding" operation.

One arrangement of the invention is set forth in the following description, drawings and claims.

Referring to the drawings, Fig. 1 is a side elevation; Fig. 2 is a section upon the line 2-2 of Fig. 1; Fig. 3 is a side elevation of one of the friction disks used for the closing operation and taken upon line 3-3 of Fig. 2; Fig. 4 is an elevation of the disk utilized for the opening operation taken upon the line 4-4 of Fig. 2; Fig. 5 is a sectional view of the lower part of the machine looking from front to rear with parts broken away to clearly show the mechanism; Fig. 6 is a top plan view of the treadle mechanism; and Fig. 7 is a section upon the line 7-7 of Fig. 6.

In the arrangement shown 1 represents the main frame provided with a rearwardly and upwardly extending supporting arm 2 and with an upwardly extending bed support 3 for a hollow heated buck or bed 4 provided with suitable padding 5. The upper padded face of the buck 4 is substantially in the same horizontal plane as the upper end of the arm 2. Mounted upon a suitable pivot 6 of arm 2 is a head lever comprising a forwardly extending portion 7 and a rearwardly extending portion 8. The forward end 7 of the head lever is provided with a suitable hollow steam-heated head 9 which in the laundry press is polished for ironing purposes and in the garment press may have a covering 10 for giving the desired finish to woolen and other outer garments.

Extending upwardly from the frame 1 at the rear of the machine are suitable eyes 11 receiving a pin 12 upon which is mounted a lower toggle link 13. This lower toggle link is pivotally connected to an upper toggle link 14 extending upwardly through a swivel head 15 pivotally mounted at 16 in

the rear portion 8 of the head lever. The upper end of the link 14 is provided with a suitable stop 17 secured to the end thereof and adapted to engage the top of the head 15. A spring 18 is arranged below the head 15 and engages a suitable adjusting means 19 threaded upon the link 14. The spring 18 forces into engagement the stop 17 and the head 15 so that when the press head is 10 closed the yielding pressure of the spring 18 is exerted upon the rear portion 8 of the head lever and the press head is yieldingly pressed down upon the garment. The toggles formed by the links 13 and 14 are normally broken to the right as shown in Fig. 1 when the head is open and are straightened to close the head by a transverse link 20 pivotally connected to a crank 21. This crank 21 is provided with a supporting shaft portion 22 and a drive shaft 23 projecting outwardly on the left hand side of the frame, as viewed from the front of the machine, the shaft 23 being driven by suitable power mechanism to be described.

25 It is obvious that when the crank 21, as shown in Fig. 1, is rotated counter-clockwise through 180° the main toggles 13 and 14 as well as the toggles formed by the link 20 and crank arm 21 will all be straightened 30 and the head will be moved down with great pressure upon the work. This type of mechanism is similar to mechanism already disclosed in this art and merely represents one form of head closing and pressure applying 35 means capable of being used with this type of mechanism and is set forth merely because it forms a part of the organization.

The specific subject matter of this invention relates to the power mechanism, its application to the head closing and opening means and the control of the same. The power mechanism comprises a closing friction disk member 24 having a segmental friction surface 25 and a hub portion 26, as 40 well as an opening disk member 27 having a friction segment 28 and a hub portion 29. The friction segments are set into the faces of these disks. These two friction disk members may be made as a unitary structure if desired but in the present arrangement they are connected into a single unit by suitable bolts 30. The combined hubs of these two disk members are provided with the keyway 31^a for engagement with a relatively long key or spline 31 upon the shaft 23. The friction disk unit is readily movable endwise upon the shaft 23 for the establishment of drive connection for the press closing and opening operations, as will appear. Mounted upon a suitable bracket 32 secured to the frame is a motor 33 operating through the usual worm and worm wheel drive to rotate a main driving shaft 34 which projects radially between the two disk members 24 and 27 and is there provided with

a driving member 35 keyed or otherwise suitably mounted upon said shaft. This driving member is of a size such that it may be rotated freely in neutral position between said disk members without engaging either 70 one, but when one of said disk members is brought into engagement with the driving member the disk member will be driven in the proper direction to perform the closing or opening machine function as the case may be. 75

The closing disk 24 has an arc-shaped friction segment 25 already referred to and best illustrated in Fig. 3 and the extent of this friction segment is such that it terminates at a point indicated at 36 which so positions 80 the crank 21 that the toggles are all straightened and moved past their straight line positions so that the press is locked closed. It may be that only one set of toggles, for example the main toggles, are moved beyond 85 the straight line position; on the other hand, the transverse toggle may be straightened to lock the press; or, as before stated, both sets may be straightened to provide a lock. In any event the friction segment 25 is sufficient 90 in its arcuate extent to bring about a complete closing cycle, and when the end of this segment is reached the drive member 35 rides freely and without further effect, even though the operator may not have removed 95 his hand or foot from the controller which has been previously moved into the closing position, as will more fully appear.

The other friction disk member 27 is provided with a similar friction portion 28, already referred to, and the arcuate extent of this friction portion is such that when this friction member is moved into engagement with the member 35 the friction surfaces are engaged and the press is opened. The end 100 of the segmental friction portion 28 determines the extent of the opening movement, just as the end of the friction segment 25 determines the end of the closing operation. The parts as positioned in Fig. 4 and the directions of rotation therein indicated are those which prevail when the press is standing open, it being obvious that when the press is closed the friction portion 28 will occupy the opposite position. The engagement of 105 one or the other of the friction disks with the drive member may be brought about by any suitable mechanism, but in the arrangement shown most clearly in Figs. 5, 6 and 7 the frame is provided with a bracket 37 supporting a bell crank lever comprising an upwardly extending portion 38 provided with an idle roller 39 extending between the two friction disks 24 and 27 and adapted to engage the faces thereof outside of the friction portions as shown. This lever also has another arm 40 bent around in L-shape and extending within the frame where it is provided with a pin 41 adapted to engage in a slot 42 in the rear extension 43 of a treadle 110 115 120 125 130

44. This lever is provided with an adjustable counter-weight 40^a which tends to move the lever in a counterclockwise direction and balance the entire lever structure and thereby 5 assist the neutralizing device to function.

This bell crank control lever comprising the parts 38 and 40 can be held in neutral position to hold both disks out of engagement with the drive member so that the pressing 10 members may be held locked in closed position. This is accomplished by a spring-controlled cam means arranged on one side of the treadle member and comprising a cam member 45 receiving a plunger 46 secured to the 15 treadle and surrounded by a spring 47. The cam member 45 engages a corresponding cam face on the fixed member 45^a which co-operates therewith in the action here described. The cam member is actuated by depression of 20 the treadle against the tension of spring 47 and is limited in its movement by pin 48 engaging in slot 49. The spring-controlled cam means is so arranged that the treadle member is held in a middle or idle position whereby 25 the operator may close the press and lock it, release the control and let the press remain closed. In other words, upon releasing the treadle it is set and held in neutral position by the mechanism just described. He may 30 then open it, as will appear.

When the press is open and the motor is running, the operator may depress the toe portion of the foot plate or treadle to shift the friction members to the right, causing the 35 drive member 35 to engage the closing disk 24. This operation starts the straightening of the toggles and if continued will result in the closing of the press and the creation of final pressure and ultimately will result in 40 the locking of the press. If the operator should desire to release the press at any stage, except at the extreme end of the final pressure, he may do so by merely raising his toe which releases the drive and automatically re- 45 turns the treadle to neutral position; and if the head lever is provided with a counter-weight or with opening springs, such as the spring 8^a, the head will move upwards towards open position. If no automatically 50 acting opening means, such as a spring or a counter-weight, is provided, the operator may easily raise the head by physical effort, due to the fact that the head is easily and readily movable when the power means has been 55 disconnected therefrom. It makes no difference how far the head moves toward open position, the operator may again close the press at once by depressing the toe portion of the foot plate or treadle; and this so-called 60 65 "pattin'" operation may be rapidly repeated, according to the desire of the operator. By merely varying the pressure applied by the operator to the control pedal or foot plate 44, the slip action between the friction members 70 may be varied and the closing and opening

movements of the head thereby varied. This enables the operator to slow up the closing movement of the head as said head approaches the bed or buck, if desired. If the press is provided with an opening spring 8^a 70 and does not open of its own accord, as for instance if in locked position, the operator may depress the heel portion of the treadle and thereby shift the disk member unit into release or press opening position, whereupon 75 the power will operate to open the press. It will be understood that except when the press is locked closed, power means is not necessary for opening the press if it is provided with an opening spring 8^a as the spring 8^a 80 will open the head upon release of pressure upon the toe of the treadle. However, when the press is held locked in closed position by the fully straightened condition of the toggles, the motor is necessary to release the 85 press. Thus, the spring 8^a may or may not be included in the present structure, as desired.

Thus I have produced a press which is not only capable of increased efficiency but at the same time is of comparatively simple 90 operation and is extremely safe. Its high degree of safety is seen from the fact that should the operator's hand be touched by the descending head, he may at once preclude any danger by removing his foot from the 95 treadle, whereupon the head is prevented from further closing movement by the automatic breaking of the driving connection, the driving disk returning to neutral position; and, in case an opening spring 8^a is used, the 100 press head will be automatically returned to fully open position.

What I claim is:

1. A pressing machine, comprising relatively movable pressing members, means 105 adapted when actuated to close and open the press and including a friction member, means normally tending to actuate said press closing and opening means so as to effect the automatic opening of the press, power means 110 including a driving member, and means for effecting operative engagement of said driving member and said friction member, whereby the press may be opened and closed by said power means, said engagement effective means being capable of actuation to effect at any time during the closing of the press the disengagement of said driving member and said friction member, the disengagement of said members rendering the 115 press closing and opening means free for actuation by said press opening means so as to automatically effect the opening of the press.

2. As in claim 1 wherein the friction member comprises a pair of opposed friction disks spaced apart and the driving member cooperating therewith is of less diameter than the distance between the disks whereby the disks comprising the driving member 120 130

may be shifted relatively to the driving member to bring about driving engagement between one of the disks and the driving member.

5 In testimony whereof I hereby affix my signature.

BLUFORD W. BROCKETT.
